DISPLAY DEVICE FOR A LOCK OF HAIR

Ruth M. Cathcart, Grundy Center, Iowa

Application February 3, 1955, Serial No. 34,352

Term of patent 14 years

(Cl. D29—20)

FIG. 2

FIG. 1

Fig. 1 is a front elevational view of a display device for a lock of hair showing my new design, with the major portion of the glass broken away for purpose of illustration, and

Fig. 2 is a reduced rear perspective view thereof.

I claim:

The ornamental design for a display device for a lock of hair, as shown and described.
